UNITED STATES PATENT OFFICE.

ALFRED J. FLAUDER, OF BRIDGEPORT, CONNECTICUT, ASSIGNOR TO THE WEIDLICH BROS. MFG. CO., INC., OF BRIDGEPORT, CONNECTICUT, A CORPORATION OF CONNECTICUT.

DESIGN FOR A BASKET.

Application filed September 13, 1922. Serial No. 3,714. Term of patent 7 years.

To all whom it may concern:

Be it known that I, ALFRED J. FLAUDER, a citizen of the United States, and a resident of Bridgeport, in the county of Fairfield and State of Connecticut, have invented a new, original, and ornamental Design for a Basket, of which the following is a specification, reference being had to the accompanying drawing, forming a part thereof, and in which—

Fig. 1 shows a top plan of a basket embodying my new design;

Fig. 2 is a side elevation of the same; and Fig. 3 shows both a front and rear elevation of my new design.

I claim:

The ornamental design for a basket substantially as shown.

Signed at Bridgeport, in the county of Fairfield and State of Connecticut, this 11th day of September, A. D. 1922.

ALFRED J. FLAUDER.
